C. M. MARKHAM

ADJUSTABLE SHORE

Filed Dec. 15, 1924

Patented Dec. 6, 1927.

1,651,610

UNITED STATES PATENT OFFICE.

CHARLES M. MARKHAM, OF INDIANAPOLIS, INDIANA.

ADJUSTABLE SHORE.

Application filed December 15, 1924. Serial No. 755,867.

It is the object of my invention to provide a simple and convenient adjustable shore for raising or supporting objects, and particularly for use in supporting forms for concrete structures. The present invention is an improvement over the device of my prior Patent No. 1,349,576, and has several features of advantage not possessed by my prior shore. Among such advantages are greater adaptability, cheapness of construction, a more positive operation, and other advantages which will appear hereinafter.

I accomplish the above objects by providing two telescoping members, the longitudinal relative position of which may be adjustable, and which may be held positively in adjusted position.

The accompanying drawing illustrates my invention: Fig. 1 is a perspective view of my adjustable shore; Fig. 2 is an enlarged perspective view showing details of the sliding head and locking mechanism, with the head in raised position; Fig. 3 is a perspective view showing the method employed for raising the inner of the two telescoping members; Fig. 4 is a side elevation showing part of the outer of the two telescoping members broken away, and a sliding head in its lower position; Fig. 5 is a perspective view illustrating details of the sliding head and locking dogs; Fig. 6 is a plan view showing certain details of construction; Fig. 7 is a detail showing the preferred construction of the base of the outer of the two telescoping members; and Fig. 8 is a detail view showing the preferred form of the two locking dogs.

My adjustable shore comprises a lower tubular member preferably formed of two opposed channels 10 held in spaced relation by a base plate 11, struts 12, and a band 12' of sheet metal which passes around both channels 10. Slidably mounted on the top of the lower member is a head 13 pivotally supporting two dogs 14 which are adapted to engage and hold in adjusted position the member 15 which extends into the lower part of the shore formed by the channels 10. Slidable transversely of the column between the head 13 and the band 12' are two keys 16. The upper surface of each key 16 is provided with teeth 17 complementary to teeth 18 on the lower side of the head 13. The keys 16 are provided at their ends with down-turned fingers 19 which serve as stops to limit the sliding movement of such keys. The fingers 19 on each key are spaced so as

to limit the sliding movement of the keys between the position shown in Figs. 1 and 2 with the teeth 17 and 18 abutting against each other and the position shown in Fig. 4 with the teeth 17 fitting in the spaces between the teeth 18. As a guide for each sliding key 16 I provide a plate 20 spaced from the flanges of the channels 10 to provide a guideway in which each key 16 may slide. Conveniently, each plate 20 is provided with an in-turned finger 21 engaging a slot in the key 16. This finger serves to retain the key 16 in its guideway and may also serve as a stop to limit the sliding movement of such key. Slidably mounted on the side of the head 13 is a plate 22, the ends of which are preferably bent around the adjacent sides of the head 13. These in-turned ends serve as guides for the sliding plate 22, assisting in this respect the shouldered rivets 23 passing through slots 24 in the plate 22. On the top surface of each key 16 there is provided a shoulder for co-operation with the sliding plate 22. This shoulder may conveniently be one side of the end tooth 17. With the keys 16 in the position farthest to the right as shown in Fig. 2, the sliding plate 22 engages the shoulders on the keys 16 and prevents movement of such keys to the left. With the keys in their right-hand position as shown in Fig. 2, the teeth 17 abut against the teeth 18 and maintain the sliding head 13 in raised position. When it is desired to lower the head 13 for a purpose hereinafter to become evident the sliding plate 22 is raised and the keys 16 moved to the left where the teeth 17 will fit in the spaces between the teeth 18 when the head is lowered.

The dogs 14 carried by the head 13 are roughly L-shaped in cross section. Each dog 14 is provided on its opposite ends with two alined bosses 30 which are received in holes 31 in the members forming the sides of the head 13. While these bosses 30 could serve as pivotal supports to the dogs 14, I prefer to use them only to prevent the dogs from accidentally coming out of the head 13; and to this end, I make the bosses 30 considerably smaller in diameter than the holes 31 which receive them. By this construction, it is not necessary that the thrust exerted on the dogs by the telescoping member 15 be transmitted to the head 13 through these comparatively short bosses, but the lower ends of the dogs 14 may rest in a corner formed by the vertical wall 32 and the

sloping wall 33 of the head 13 and the thrust transmitted to the head throughout the entire length of the dogs. The sloping walls 33 permits the dogs 14 to drop below the horizontal position in order that comparatively thin beams 15 may be used. I prefer to use for the telescoping member 15 wooden beams conveniently square in cross-section. As such beams may vary considerably in thickness, I prefer to make those faces of the dogs 14 which engage the member 15 in the shape of a logarithmic spiral in order that the force exerted on the dogs by the member 15 will always approximate in direction to the lines A—B of Fig. 8 irrespective of the thickness of the timber. By so shaping the working faces of the dogs 14, they will grip and hold effectively beams of varying sizes.

The means I employ for adjusting the relative longitudinal position of the inner and outer telescoping members is illustrated in Fig. 3 and comprises a U-shaped jaw 40, adapted to straddle the member 15, and connected by a link 41 to a raising lever 42, the end of which is conveniently downturned to engage the lip 43 on the head 13. As the outer end of the lever 42 is raised, the member 15 is raised and is held in raised position by means of the dogs 14. When the outer end of the lever 42 is lowered, the jaw 40 drops and when the lever 42 is again raised the member 15 is gripped by the jaw 40 and raised again.

In using my shore, the head 13 is raised and held in raised position by moving the keys 16 to the position shown in Fig. 2 where their teeth 17 abut against teeth 18 of the head. The sliding plate 22 drops behind the shoulders on the keys 16 and prevents accidental displacement of such keys. The member 15 is then raised by means of the raising lever 42 in the manner above described against the object which it is desired to support. The dogs 14 serve to hold the member in place against the object supported. When it is desired to remove the shore, the plate 22 is lifted and the keys 16 moved to the position in which the teeth 17 enter the spaces between the teeth 18, whereupon the head 13 and the member 15 drop a slight distance varying with the depth of the teeth 17. This lowering of the head permits the slight rise of the member 15 which is necessary to disengage the dogs 14. With the head lowered, the dogs 14 may be disengaged and the member 15 allowed to drop into the tubular support formed by the channels 10.

To further increase the adaptability of my shore I preferably provide in the base plate 11 one or more holes 11'. Should it be desired to use my shore in a horizontal or inclined position, the holes 11' may be conveniently employed to support the shore.

I claim as my invention:—

1. An adjustable shore, comprising a hollow base, a rectangular member longitudinally slidable in said base, a head longitudinally adjustable on said base, means carried by said head for locking said member and said head in fixed relative position, and a key operating between said head and an abutment on said base and movable laterally of said base to adjust the longitudinal position of said head. 70

2. An adjustable shore, comprising a base, a member longitudinally slidable in said base, a head longitudinally adjustable on said base, means carried by said head for locking said member and said head in fixed relative position, a key operating between said head and an abutment on said base and movable to adjust the longitudinal position of said head, and means for holding said key in fixed position. 80

3. An adjustable shore, comprising a base, a member longitudinally slidable in said base, a head longitudinally adjustable on said base, means carried by said head for locking said member and said head in fixed relative position, a key operating between said head and an abutment on said base and movable to adjust the longitudinal position of said head, said key having a shoulder, and a sliding plate mounted on said head and adapted to engage said shoulder to prevent accidental displacement of said key. 90

4. An adjustable shore, comprising a base, a member longitudinally slidable in said base and means for holding said member and base in adjusted position, said means including a dog and a support therefor, said support being mounted on said base, and said dog having a curved face adapted to engage said slidable member and also having opposite said curved face a face adapted to bear against said support and to transmit to said support the force exerted on said dog by said slidable member. 100

5. An adjustable shore, comprising a hollow base formed of two opposed channel members, a rectangular member longitudinally slidable in said base, a head longitudinally adjustable on said base, means carried by said head for locking said member and said head in fixed relative position, and a key operating between said head and an abutment on said base and movable laterally of said base to adjust the longitudinal position of said head. 110

6. An adjustable shore as set forth in claim 4 with the addition that said dog is provided with two coaxial bosses and said support is provided with a hole for the reception of each of said bosses. 120

7. An adjustable shore as set forth in claim 4 with the addition that said dog is provided with two coaxial bosses and said support is provided with a hole for the reception of each of said bosses, said holes being of ma- 130

terially larger diameter than said bosses.

8. An adjustable shore, comprising a hollow base formed of two opposed channel members, a rectangular member longitudinally ⁵ slideable in said base, a head longitudinally adjustable on said base, means carried by said head for locking said member and said head in fixed relative position, and

means for adjusting the longitudinal position of said head. ¹⁰

In witness whereof, I have hereunto set my hand at Indianapolis, Indiana, this 2d day of December, A. D. one thousand nine hundred and twenty-four.

CHARLES M. MARKHAM.
